UNITED STATES PATENT OFFICE.

HARRY LANDSIEDEL, OF POPLAR BLUFF, MISSOURI, ASSIGNOR TO DALTON ADDING MACHINE COMPANY, OF ST. LOUIS, MISSOURI, A CORPORATION OF MISSOURI.

ADDING AND RECORDING MACHINE.

1,145,599.

Specification of Letters Patent.

Patented July 6, 1915.

Application filed December 2, 1909. Serial No. 530,949.

To all whom it may concern:

Be it known that I, HARRY LANDSIEDEL, a citizen of the United States, residing at Poplar Bluff, Missouri, have invented a new and useful Adding and Recording Machine, of which the following is a specification.

This invention relates to adding and recording machines of the cross carriage type, and it consists in the novel combination and arrangement of the devices embodied therein as fully shown in the accompanying drawings and hereinafter described.

Another type of machine to which this invention relates has been patented to Harry H. Helmick in Letters Patent of the United States No. 630,053, dated August 1, 1899, and re-issued December 27, 1904, under No. 12,296. An advanced or improved type of this machine is disclosed in an application for a combined adding and writing machine filed by Hubert Hopkins January 24, 1902, having Serial Number 140,390, and eventually in Patent No. 1,039,130, of September 24, 1912.

It is more specifically in combination with the Hopkins machine that this invention is illustrated and described herein, though it will be obvious that it may be embodied in any machine of the type referred to in which there is a movable pin carriage in which the numbers are set up or represented through the action of keys or otherwise.

One object of the invention is to equip such a machine with a carriage of improved construction having number-representing devices therein and guide-ways by which the number-recording devices are properly guided and prevented from injurious vibrations which sometimes result in incorrect operation of the machine.

Another object is to provide in combination with a carriage and the recording mechanism, tabulating devices under the control of the operator whereby the carriage may be caused to move from its idle or rest position to the position previously occupied by it adjacent to the recording devices at a single operation, the number-representing devices in the carriage being continuously in their operative adjustments. By this mechanism any number which has been recorded or added may be "repeated" simply by the

manipulation of the tabulating mechanism whereby the carriage will be caused to move automatically to proper position for the operation of the recording or adding mechanisms to repeat said number.

A further object is to improve adding machines of the type which include a movable carriage operation of which is necessary before the adding and recording mechanisms may be operated, and an escapement controlling the carriage, in combination with tabulating mechanism for said carriage, tabulating stops carried by the carriage and settable selectively by the tabulating mechanism to stop the carriage in different selected positions, a connection between the tabulating mechanism and the escapement whereby, when the carriage is in one position, the tabulating mechanism may be operated effectively to release the escapement without setting any of the tabulating stops, and when the carriage is in another position, operation of the tabulating mechanism will set one of the tabulating stops without releasing the escapement.

There are other objects to be attained by this invention than those specifically mentioned, all of which are intended to be made clear by the following description, reference being made to the drawings.

Figure 1 is a side elevation of an adding and recording machine in which my invention has been embodied, parts of the case being removed in order to disclose the connections from the tabulating key to the device controlled thereby. Fig. 2 is a longitudinal sectional view of the machine illustrating the automatic devices for restoring the pin carriage to idle position after each number has been added or recorded. Figs. 3 and 3^a are specimens of records performed by such machine and illustrate the purpose of the present invention. Fig. 4 is a vertical section of a portion of the machine illustrating the arrangement of the movable carriage and a part of the tabulating mechanism in connection therewith. Fig. 5 is a perspective view of the device whereby the "9" key controls the carriage. Fig. 6 is a plan view of the carriage and associated mechanism. Fig. 7 is a sectional view taken in front of the carriage. Fig. 8 is a rear

side elevation of a guide plate associated with the recording mechanism and the carriage. Fig. 9 is a rear elevation of the carriage and the tabulating mechanism. Fig. 5 10 is a cross sectional view of the carriage. Fig. 11 is a longitudinal sectional view of the tabulating stop devices. Fig. 12 is a cross sectional view of the tabulating device taken 10 on the line 12—12 of Fig. 11. Fig. 13 is a 15 similar view taken on the line 13—13 of Fig. 11.

The keys 10 are arranged in convenient 15 relation at the front of the machine, having levers 11 projecting rearwardly and terminating in a row from front to rear. The 20 said keys are ten in number, there being one for each of the ten digits or figures. The rear end of each lever, except the one for "9", is provided with a vertical extension or hammer 12, above which the movable carriage 13 operates. Said carriage is supported on rails 14 by means of anti-friction 25 rollers 15. Said rails extend transversely and the carriage travels thereon in its movement from order to order when the number 30 keys are operated. The carriage is provided with projections 16 extending into channels or grooves in the rails 14 and serving as retainers to prevent removal of the carriage 35 from the rails.

As usual, the carriage includes a series of 35 rows of pins 17. Said pins are actuated downwardly by springs 18, Fig. 10, but may be moved vertically to registering position 40 by operation of the number-keys, the extensions or hammers 12 engaging the lower ends of the pins when the said keys are operated, thereby moving the pins to registering position. Sliding latch plates 19 are arranged in proper relation with the 45 rows of pins, whereby when any pin is raised it will be supported in its raised position until another pin in the same row is operated, whereupon the latch plate will be 50 moved to release the first pin and to engage with and support the second pin. In the upper portion of the carriage the upper ends of the pins extend into grooves or channels 55 within which the heels 21 of the racks 22 travel when operated to record numbers set up in the carriage. The racks 22 in the 60 present instance, just as in the Hopkins patent referred to, swing from the shaft 23 and are co-operatively related to type carriers 24 swinging from the same shaft and 65 operable effectively to record upon the platen A. the numbers successively set up or registered in the pin carriage. The racks 22, as in the Hopkins patent, also operate the 70 adding mechanism B. to register or add therein the numbers contained in the carriage when the racks are operated. The mechanism for effecting intermittent connection of the adding mechanism with the 75 racks is too well known at the present time

to require further description herein, it being understood that the adding mechanism is disengaged from the racks during operation of the latter in one direction, and engaged therewith when the racks are operated in the other direction causing the adding mechanism to operate to add numbers in the usual and well known way. As in said patent the carriage in the present instance is controlled by an escapement device which 80 may be of any preferred type operable by the keys. In the present instance an escapement bar 25 rests upon the key levers 11 and is provided with a pawl 26 arranged to escape upon a segment 27 attached to the 85 vertical shaft 28. Said shaft 28 has an arm 29 secured at its upper end and connected with the carriage by a pivoted link 30 whereby by rotation of the shaft in either direction will cause corresponding movement of the 90 carriage. An arm 31 is rigid with the shaft 28 and is actuated by a spring 32.

From the foregoing it will be seen that 95 operation of the key levers 11 will result in operation of the escapement permitting the 100 spring 32 to move the carriage step by step across the machine to proper position with respect to the racks 21 and the type carriers 24. The operation of the key levers also results in setting the pins 17 to represent the number struck on the keys except as to the "9" key which, as previously 105 stated, is without any pin-setting device. The lever for the "9" key is provided with a standard 33, at the upper end of which a lever 34 is pivoted, said lever having one arm extending vertically and another arm extending under the adjacent rail 14. A spring 35 holds said lever in its idle position as shown in Fig. 4. Operation of the 110 "9" key will cause the horizontal arm of the lever 34 to engage the under side of the adjacent rail 14 and will cause the vertical arm of said lever to engage the front end of one of the plates 19 effectively to move 115 said plate rearwardly and release any pin that may have been previously set in operative position. There is no pin 17 for the "9" key, the plate 36 being secured to the front side of the carriage in front of all of 120 the rows of pins, said plate acting as an abutment for the heels 21 in operation of the racks and recording devices for adding and recording 9's. The plates 19 move successively past the lever 34 in the same way 125 that the pins 17 move successively over the key hammers 12. After each number is added or recorded the carriage is returned to its position as shown in Fig. 6, the number which had been registered in 130 the carriage and had been recorded or added being yet retained in the carriage, since the pins are supported by the plates 19 until released by operation of other pins as previously mentioned.

The machine of the Hopkins patent includes a rock shaft 60, (Fig. 2), which is rocked forwardly and rearwardly as a necessary accompaniment of recording and adding operations. An arm 61 is supported on the shaft, and the springs 62 are arranged to rock the shaft to restore it to idle position after each number has been recorded, in the well understood manner. A link 63 has its upper end pivoted upon a stationary support, and its lower end pivoted to the front end of a link 64. A rack 65 on the rear portion of said link meshes with a segment 66 loosely mounted on the shaft 28 and having a pin 67 extending downwardly therefrom. A pin 68 extending upwardly from an arm 69 which is rigidly attached to the shaft 28 is in the path of movement of the pin 67. When the carriage 13 moves from its idle position the arm 69 moves with the shaft 28 and carries the pin 68 toward the pin 67, so that rearward movement of the link 64 will actuate the segment 66 and engage the pin 67 with the pin 68 effectively to rock the shaft 28 and restore the carriage 13 to its idle position through the medium of the meshing segment 29 and rack 30. A spring 70 connects the link 63 with a stationary part of the machine and yieldingly holds the link 64 in its forward position. The link 63 is provided with a pin 71. The upper end of the arm 61 supports a hook 72 which is provided with a vertical arm arranged to engage with a stationary part 73 when the shaft 60 is at rest, and thereby holds the hook 72 in a plane below the pin 71. When the shaft 60 is rocked forwardly, which is necessary in order to record the number set up in the carriage 13, the hook 72 is carried forwardly and is raised by the tension of a spring 74 connecting a rearward extension of the hook to a projection on the arm 61. When in its forward position the hook 72 engages the pin 71, so that when the shaft 60 is rocked to its idle position by the spring 62 the hook 72 will actuate the links 63 and 64, and thereby rock the shaft 28 because of the engagement of the pin 67 with the pin 68 as above explained. This return movement of the shaft 60 after any number has been recorded or added in this manner automatically returns the carriage 13 to its idle position. As the hook 72 approaches its idle position the upper arm thereof engages the stationary part 73 and thereby disengages said hook from the pin 71, after which the spring 70 retracts and moves forwardly the links 63 and 64. These devices have their substantial counterpart in the machine of the Hopkins patent, and in the Dalton adding machine which has been manufactured in substantial conformity with said patent.

From the foregoing it will be seen that in order to repeat any number previously represented in the carriage after the carriage has returned to idle position, it will be necessary only to move the carriage to proper position with respect to the type carriers and racks, and that no operation of the pins in the carriage would be required. This operation can be effected either by operating the number keys again which will permit the carriage to be moved step by step, or it may be effected by the tabulating mechanism causing the carriage to be moved at a single operation to its proper position.

The subject-matter of the present invention includes such tabulating mechanism and comprises a tabulating key 37 operatively supported in convenient position and having its stem extending through an opening in the case of the machine and resting upon one arm of the bell-crank lever 38, the opposite arm of which is connected by a link 39 with a lever 40 attached to a rock-shaft 41 supported by the side frames of the machine at the rear of the carriage 13. A spring 42 encircles the stem of the key 37 returning the same to idle position after each operation. The shaft 41 is movable to a slight extent longitudinally in its bearings, being actuated leftwardly by a spring 43 interposed between the lever 40 and the side frame. To the rear side of the carriage 13 a frame or housing 44 is secured, which, in idle position of the carriage engages against an arm 45 on the shaft 41, thereby holding said shaft in its idle position in opposition to the spring 43 thereon. The first step or movement of the carriage, however, will permit the shaft 41 to be moved by the spring 43 a distance sufficient to carry the horizontal arm of the bell-crank lever 40 over the vertical extension of a lever 46 which is pivoted to the rail 14 at the rear. Thus in idle position of the carriage the tabulating key and mechanism are ineffective to operate the lever 46 and said lever may be operated only after the carriage has moved one or more spaces. The opposite end of the shaft 41 supports a lever 47 extending over the tail of the pawl 26 when the shaft 41 is held in idle position by the carriage. Operation of the tabulating key therefore will cause the lever 47 to release the pawl 26 from the segment 27 and permit the carriage to be moved one or more spaces until stopped by other devices than the pawl. The arrangement in this connection is such that when the tabulating key is depressed the spring 43 will be ineffective to actuate the shaft 41 until said key is released, thereby retaining the lever 47 in engagement with the pawl 26 throughout the operation. Release of the tabulating key 37 disengages the lever 47 from the pawl 26 and permits the spring 43 to actuate the shaft 41 to the left with respect to the oper-

ator, thereby moving the lever 47 beyond the pawl 26 and placing the front end of the lever 40 over the end of the lever 46.

Within the housing or frame 44 a row of pins 48 are mounted, said pins being arranged in alinement with the respective rows of pins 17. The pins 48 are arranged vertically being movable through holes in the upper and lower sides of the frame 44 and actuated to their lower positions by encircling springs 49 mounted between ribs 50 on the pins and the upper side of the frame. A sliding plate 51 is mounted in the frame and is actuated in one direction by a spring 52. Pins 48 extend through holes in said plate 51, the ribs 50 in idle position of the pins press against the upper side of said plate. Each pin is provided with a beveled rib 53 normally below the plate 51 but operable when pressed upwardly to engage against the plate and operate it in opposition to its spring 52 until said rib 53 has passed above the plate, at which time the plate will be moved under the rib and latch the pin in its elevated position as shown in Figs. 11 and 13. It will be obvious also that when any one of these pins is thus supported operation of any other pin will move said last named pin to latched position above the plate 51 and will release the pin previously in such adjustment, permitting its spring to return it to idle position.

When the carriage moves leftwardly on operation of the number keys, the pins 48 are carried successively over one end of the lever 46 as may be seen by reference to Fig. 9. Also the leftward movement of the carriage causes the lever 40 to be placed in operative relation with respect to the lever 46. Therefore, after any number whatever has been set within the carriage, the tabulating key may be operated effectively to cause the lever 46 to move one of the pins 48 to elevated position as shown in Fig. 11. The pin so moved in any case will be rearwardly from that row of pins 17 in which, or in advance of which by operation of the "9" key, the last digit struck on the keys was registered. Operation of the recording mechanism will then cause the carriage to be returned to idle position as is well understood, but the pins 17 which had been set to register the number and the pin 48 which had been elevated will all be retained in their upper adjustments. As previously stated, the carriage may now be caused to move to operative position with respect to the racks 22 and their associated type carriers 24 by operation of the tabulating key which releases the escapement and permits such movement. It is necessary, however, that some device be provided to stop the carriage at the proper position and to prevent it from being moved beyond the desired loca-

tion. I will now describe this stopping device.

The shaft 41 has an arm 54 loosely mounted thereon and extending through a notch in a stationary plate 55 to which said arm 54 is connected by a supporting spring 56 preventing said arm from dropping but permitting actuation thereof when desired. The plate 55 prevents lateral movement of the arm 54 when the shaft 41 is moved by its spring 43 or by operation of the pin carriage. The sleeve to which the arm 54 is attached has a pin 57 extending laterally in front of a pin 58 rigid with the shaft 41 whereby rotation of the shaft by operation of the tabulating key will cause the arm 54 to swing downwardly into position to be engaged by the tabulating stop pin 48 which had previously been raised. Thus the carriage will be stopped in position to present the previously registered number in proper relation to the racks and their type-carriers so that said number may be repeated as often as desired without operation of the number keys. Release of the tabulating key at this time will permit the escapement pawl 26 to engage with the segment 27 and thereby hold the carriage from further movement. The arm 54 will also be raised as soon as the tabulating key is released and before or after the previously registered number has been added or recorded any other numerical key may be actuated effectively to register in the carriage any other digits in lower orders from the number already therein. This is possible for the reason that the arm 54 in idle position is at such altitude that the pins 48 in their elevated position may pass thereunder. At any position of the carriage after any digit key has been struck, the tabulating key may be operated effectively to position the desired tabulating stop pin, provided the same has not been positioned at some other time, and to permit any other tabulating stop pin to be returned to idle position.

A tabulating mechanism of this character in connection with these machines is especially valuable wherever multiplying or repeating of numbers is required. By this mechanism any number registered in the carriage may be added or recorded as often as desired, and after the carriage has been returned to idle position and the adding mechanism cleared, the machine may be put into immediate operation for repeating the same number further without the necessity of again setting said number in the carriage, and the manipulation of a single key is all that is required to cause the carriage to move to the required position irrespective of the number of digits in the number to be added or recorded. The same key controls the stop-setting mechanism of the tabulating devices and the escapement release,

thereby avoiding confusion and opportunity for error as would arise from the provision of separate keys for these purposes.

I have illustrated my invention embodied 5 in a machine such as described in the application aforesaid filed by Hubert Hopkins and in the Hopkins patent in England, but I do not restrict myself to its use in machines of that specific type since it may as 10 well be used in connection with any machine having a movable pin carriage, whether the pin carriage constitutes the stop mechanism for the adding and recording devices or is merely a register utilized for other purposes. But

What I claim and desire to secure by Letters Patent of the United States is—

1. In an adding machine, the combination 20 with a carriage, devices for setting up numbers in said carriage and moving said carriage to operative position with respect to the recording mechanism, and mechanism for recording said numbers and restoring said carriage to idle position, of an abutment 25 separate from said carriage, stops carried by said carriage, a key operable in certain positions of said carriage to set said stops and operable in another position of said carriage to position said abutment for engagement with said stops, means controlled by said key for positioning said carriage in operative position with respect to said recording mechanism, and means for disabling the last-named function of said key 30 incidentally to the movement of said carriage to operative position with respect to the recording mechanism.

2. In an adding machine, the combination 40 with differential mechanism, and means for moving said differential mechanism to and from position to coöperate with adding mechanism, of devices under control of the operator for positioning said differential mechanism in the position it occupied in a previous operation, and means disabling said devices incidentally to the movement of said differential mechanism.

3. In an adding machine, the combination 50 with differential mechanism settable to represent numbers, devices for setting said differential mechanism to represent numbers, and means for moving said differential mechanism to position to coöperate with adding mechanism, of means under control of the operator for positioning said differential mechanism to coöperate with the adding mechanism in the same position it occupied in a previous operation independently of said devices, and elements disabling said last-named means incidental to the movement of said differential mechanism to position to coöperate with said adding mechanism.

4. In an adding machine, the combination 60 with differential mechanism movable into

and out of operative position, of mechanism for controlling the movement of said differential mechanism from idle position to its various operative positions, means for operating said mechanism to position said differential mechanism in any selected operative position at a single operation, and means for disabling said last-named means incidentally to the movement of said differential mechanism.

5. In an adding machine, the combination 70 with adding mechanism arranged in numerical orders, of differential mechanism controlling the operation of said adding mechanism, means for holding said differential mechanism normally out of position to coöperate with said adding mechanism, means for moving said differential mechanism to position to coöperate with any selected number of said wheels at a single operation, and elements for disabling said last-named means incidentally to the movement of said differential mechanism.

6. In an adding machine, the combination 80 with adding wheels arranged in numerical orders, racks arranged in numerical orders for operating said adding wheels, differential mechanism controlling the operation of said racks and wheels, means normally holding said differential mechanism 90 out of position to coöperate with said racks and wheels, keys for setting said differential mechanism to represent numbers to be added, means for moving said differential mechanism to position to coöperate with 95 said racks and said wheels incidentally to the operation of said keys, and independent means for positioning said differential mechanism to coöperate with said racks and wheels in adding a number added in a preceding operation.

7. In a machine of the character described, the combination with a series of type-carriers arranged in numerical orders, differential mechanism controlling the movement of said type-carriers, means for setting said differential mechanism to represent numbers and positioning said differential mechanism to coöperate with the number of said type-carriers necessary to record the numbers represented by said differential mechanism, of independent means for positioning said differential mechanism to coöperate with the same number of type-carriers which operated in a preceding operation to record the same number recorded in such preceding operation, and means for disabling said last-named means as an incident to the movement of said differential mechanism by the setting of a number 11 therein.

8. In a machine of the character described, the combination with adding wheels arranged in numerical orders, and racks arranged in numerical orders for actuating 13

- 5 said adding wheels, of differential mechanism settable to represent numbers to be added, means for positioning said differential mechanism to limit movement of the required number of racks and adding wheels in adding various numbers, independent means for positioning said differential mechanism to coöperate with said racks and adding wheels in adding the same number 70
- 10 10 added in a preceding operation, and devices for disabling said last-named means as an incident to the positioning of said differential mechanism by said first-named means.
- 15 9. In a machine of the character described, the combination with a series of type-carriers arranged in numerical orders, and differential mechanism settable to limit movement of said type-carriers in recording various numbers, of means for setting said 80
- 20 differential mechanism to limit movement of said type-carriers in recording operations, independent mechanism for positioning said differential mechanism to limit movement of said type-carriers in recording a number 85 recorded in a preceding operation, and means for disabling said independent mechanism as an incident to the setting of said differential mechanism by said setting means.
- 25 10. In an adding machine, the combination with adding wheels, racks for operating said adding wheels, differential mechanism settable to represent numbers and limit movement of said racks in operating said 90
- 30 adding wheels to add said numbers and means for setting said differential mechanism to represent said numbers, of independent means for positioning said differential mechanism to coöperate with said 95
- 35 racks in adding a number added in a preceding operation, and devices for disabling said independent mechanism incidentally to the setting of said differential mechanism to represent a number.
- 40 11. In an adding machine, the combination with adding wheels, racks for operating said adding wheels, differential mechanism settable to control said racks, and keys for setting said differential mechanism to 100
- 45 represent numbers to be added by operation of said racks and adding wheels, of means independent of said keys for positioning said differential mechanism to coöperate with said racks in adding operations, and elements for disabling said independent means incidentally to the setting of said differential mechanism by said keys, substantially as described.
- 50 12. In an adding machine, the combination with adding wheels, racks for operating said adding wheels in adding operations, differential mechanism settable to represent numbers and to limit movement of said racks in adding operations, keys for setting said differential mechanism to represent 105
- 55

numbers and controlling the movement of said differential mechanism to coöperate with said racks, of means independent of said keys for positioning said differential mechanism to coöperate with said racks to 70 add a number added in a preceding operation, and devices for disabling said independent means incidentally to the setting of said differential mechanism by said keys.

13. In an adding machine, the combination with differential mechanism movable to and from operative position, keys for setting said differential mechanism to represent numbers and controlling the movement of said mechanism to operative position, of 80 means independent of said keys controlling the movement of said differential mechanism to an operative position in which said differential mechanism was located in a preceding operation, and devices for disabling 85 said independent means incidentally to the setting of said differential mechanism by said keys.

14. In an adding machine, differential mechanism comprising a movable support, 90 means holding said support, an actuator for moving said support, movable elements mounted in said support, a manipulative device operable in one position of said support to set one of said elements and connections 95 operated by said device in another position of said support to release said holding means and to enable said actuator to move said support, substantially as described.

15. In an adding machine, differential 100 mechanism comprising a carriage, keys operable to set up numbers in said carriage, an actuator for moving said carriage, means holding said carriage, a device for disabling said holding means and enabling said actuator to move said carriage, stops settable by said device to limit movement of said carriage, and an abutment for said stops controlled by said device, substantially as described.

16. In an adding machine, differential mechanism comprising a carriage, a releasable device holding said carriage, an actuator for moving said carriage, a support, stops in said support, an abutment for said stops, a device operable in one position of said carriage to set one of said stops and operable in another position of said carriage to release said holding means and enable said actuator to move said carriage, and means for moving the stop which had been set to idle position incidentally to the setting of any other stop, substantially as described.

17. In an adding machine, the combination with a carriage, mechanism for setting up numbers in said carriage, means for moving said carriage, and mechanism for returning said carriage to its idle position after any number has been set up therein, of devices operable to cause said moving means 125

to move said carriage at a single movement to the position it occupied when a previous number was first set up therein, and means for disabling said devices incidentally to the 5 movement of said carriage from idle position.

18. In an adding machine, the combination with a carriage, mechanism for setting up numbers in said carriage, means for moving said carriage, and mechanism for returning the carriage to its idle position after each number has been set up therein, of devices operable effectively to cause said moving means to move the carriage at a 10 single movement to the position it occupied when a previous number was first set up therein, means for disabling said devices incidentally to the movement of said carriage from idle position, and means operated incidentally to the movement of said carriage to idle position to re-adjust said devices so that said devices will be restored from said 15 disability.

19. In an adding machine, the combination with a carriage, mechanism for setting up numbers in said carriage, escapement mechanism for moving said carriage, and mechanism for returning said carriage to its idle position after any number has been set 20 up therein, of devices operable to enable said escapement mechanism to move said carriage from idle position, and means for disabling said devices incidentally to the movement of said carriage from its idle position.

30 20. In an adding machine, the combination with differential mechanism key mechanism operable to set said differential mechanism to represent numbers, devices independent of said key mechanism for setting 35 said differential mechanism to represent a number set by the previous operation of said key mechanism, and means for disabling said devices incidentally to the operation of said key mechanism, substantially as 40 described.

45 21. In an adding machine, the combination with a carriage, key mechanism operable to set up numbers in said carriage, means for moving said carriage to operative position as an incident to the operation of 50 said keys, and adding and recording mechanisms for adding and recording said numbers, of stops for limiting movement of said carriage in tabulating operations, means for 55 selectively setting said stops to limit movement of said carriage in subsequent operations to the same position said carriage occupies when one of said stops is set, and means for causing said moving means to 60 move said carriage at a single operation to the position it occupied when said stop was set.

65 22. In an adding machine, the combination with adding mechanism, a series of racks for operating said adding mechanism,

and a carriage whose operation is necessary before said racks may be operated, of a series of stops carried by said carriage, means for selectively setting said stops, and means controlled by said stop setting means for moving said carriage as required to enable 70 said racks to operate.

23. In an adding machine, the combination with recording mechanism, and a movable device controlling the operation of said recording mechanism, an actuator for said movable device, a series of stops mounted on said movable device, means for selectively setting said stops to limit movement of said movable device, and means for enabling said 75 actuator to move said movable device. 80

24. In an adding machine, the combination with adding mechanism, racks for actuating said adding mechanism, a carriage whose operation is necessary before said racks may be operated, means for holding said carriage in position which said racks cannot operate, means for moving said carriage to position in which said racks may operate, a series of stops mounted on said carriage, means for selectively setting said stops, and means controlled by said stop-setting means to enable said carriage to move. 85

25. In an adding machine, differential 90 mechanism comprising a carriage, keys operable to set up numbers in said carriage, means holding said carriage, an actuator for moving said carriage, a device for disabling said holding means and enabling said actuator to move said carriage, and stops carried by said carriage and settable by said device to limit movement of said carriage. 95 100

26. In an adding machine, differential 105 mechanism comprising a carriage, a device holding said carriage, an actuator for moving said carriage, a support on said carriage, stops in said support, an abutment for said stops, and a device operable in one position of said carriage to set one of said stops, and operable in another position of said carriage to release said holding means and enable said actuator to move said carriage, substantially as described. 110

27. In an adding machine, differential 115 mechanism comprising a carriage, means holding said carriage, an actuator for moving said carriage, stops on said carriage, a manipulative device operable in one position of said carriage to set one of said stops, and means operable by said device in another position of said carriage to release said holding means and to enable said actuator to move said carriage. 120

28. In an adding machine, differential 125 mechanism comprising a carriage, means holding said carriage, an actuator for moving said carriage, stops for limiting movement of said carriage in certain operations, means for setting said stops selectively as 130

- determined by the position of said carriage, whereby one of said stops may be set in one position of said carriage and other stops may be independently set in other positions of said carriage, devices controlled by said stop-setting means for disabling said holding device and enabling said actuator to move said carriage when said carriage is in idle position, and means controlled by said 10 stop-setting means to prevent movement of said carriage as a result of operating said stop-setting means to set a stop.

29. In an adding machine, differential mechanism comprising a carriage, a device 15 for holding said carriage, an actuator for moving said carriage, stops on said carriage, a manipulative device operable in one position of said carriage to set one of said stops, means for adjusting said device by movement of said carriage to another position so that said device cannot set any one of said stops while said carriage remains in such position, and means operable by said device when said carriage is in said last-named 25 position to release said holding device and to enable said actuator to move said carriage.

30. In an adding machine, differential mechanism comprising a carriage, a device holding said carriage, an actuator for moving said carriage, stops supported by said carriage, an abutment for said stops, a manipulative device operable in certain positions of said carriage to set certain of said 35 stops, means controlled by said carriage in one position thereof to affect said device so that said device cannot set any one of said stops while said carriage remains so positioned, and means operable by said device 40 while said carriage remains so positioned to release said holding device and to enable said actuator to move said carriage.

31. In an adding machine, a laterally movable carriage, differential mechanism, means for moving said differential mechanism, a series of stops carried by said differential mechanism, a movable abutment for said stops, and a key connection operable to selectively set said stops and to move 50 said abutment in position to engage said stops.

32. In an adding machine, differential mechanism, a series of stops carried by said differential mechanism for controlling the 55 position thereof, an abutment for said stops, means for moving said differential mechanism to various selected positions, means for setting one of said stops when said differential mechanism is in one of several selected 60 positions, and means controlled by said stop setting means to enable said differential mechanism to move and to move said abutment in position to engage the stop which had been set.

- 65 33. In an adding machine, differential mech-

anism comprising a carriage, series of members in said carriage settable to represent numbers, means for moving said carriage laterally in one direction as an incident to the setting of said members, automatic 70 means for moving said carriage to its starting point, and independent means for moving said carriage to position said members to represent the number represented in a preceding operation.

34. In an adding machine, a laterally movable carriage, means for moving said carriage laterally, a support on said carriage, a row of stops in said support for limiting lateral movement of said carriage, 80 means for moving said stops selectively to position to limit movement of said carriage, mechanism controlled by said last-named means for moving a previously set stop to idle position incidentally to the setting of another stop, an abutment, means normally holding said abutment out of position to engage said stops, means for moving said abutment into position to engage one of said stops as an incident to the setting of 90 any stop, and means for disabling said stop moving means as an incident to the movement of said carriage, substantially as described.

35. In an adding machine, the combination with recording mechanism operable to record numbers set in the differential mechanism, of differential mechanism comprising a carriage, members in said carriage settable to represent numbers, means for setting said members to represent numbers and moving said carriage laterally to co-operate with said recording mechanism, means for restoring said carriage to its starting point as an incident to the operation of said recording mechanism, and independent means for positioning said differential mechanism in the same position it occupied when co-operating with said recording mechanism in the preceding operation. 100 105 110

36. In an adding machine, the combination with adding mechanism, racks for operating said adding mechanism, and means for operating said racks, of series of stops settable to represent numbers and to limit movement of said racks, a laterally movable carriage for positioning said stops to represent selected numbers to be added by the operation of said racks and said adding mechanism, means for restoring said stops and said carriage to idle position as an incident to the operation of said adding mechanism by said racks, and independent means for causing said carriage to position the same stops which co-operated with said racks in a preceding operation by a single movement of said carriage. 120 125

37. In an adding machine, the combination with adding mechanism, and actuators for operating said adding mechanism, 130

of a laterally movable carriage movable from and to a certain starting point when any number different from a preceding number is introduced in said adding mechanism, means in said carriage controlling the operation of said actuators, means for positioning said carriage to control the operation of any desired number of said actuators, and independent means for positioning said carriage to control the same actuators which were controlled in a preceding operation whereby the same number will be in-

roduced into said adding mechanism that was introduced in said preceding operation, substantially as described. 15

In testimony whereof, I hereunto affix my signature to this specification this 22nd day of November, 1909, in the presence of two witnesess.

HARRY LANDSIEDEL. [L.S.]
